CLAIM

The ornamental design for a golf swing playing aid device, as shown and described.

DESCRIPTION

FIG. 1 is a top, front, left perspective view of a golf swing playing aid device showing our new design;

FIG. 2 is a bottom, rear, right perspective view thereof;

FIG. 3 is a left elevation view thereof;

FIG. 4 is a right elevation view thereof;

FIG. 5 is a top plan view thereof;

FIG. 6 is a bottom plan view thereof;

FIG. 7 is a rear elevation view thereof; and,

FIG. 8 is a front elevation view thereof.

The broken line showing is for the purpose of illustrating portions of the golf swing playing aid device and forms no part of the claimed design.
